DESIGN FOR A BOX OR SIMILAR ARTICLE

William O. Lawson, Montclair, N. J.

Application June 14, 1944, Serial No. 113,996

Term of patent 7 years

(Cl. D58—12)

To all whom it may concern:

Be it known that I, William O. Lawson, a citizen of the United States and a resident of Montclair, in the county of Essex and State of New Jersey, have invented a certain new, original, and ornamental Design for a Box or Similar Article, of which the following is a specification, reference being had to the accompanying drawing, forming a part thereof.

In the accompanying drawing:

The broken lines in Figure 1 are used to indicate ornamentation on the underside of the cover and visible through the cover.

I claim:

The ornamental design for a box or similar article, substantially as shown and described.

WILLIAM O. LAWSON.
